UNITED STATES PATENT OFFICE

161,816

LIVE BAIT CARRIER

Rufus D. Blakeslee, Chicago, Ill.

Application November 18, 1949, Serial No. 6,118

Term of patent 14 years

(Cl. D31—4)

To all whom it may concern:

Be it known that I, Rufus D. Blakeslee, a citizen of the United States, residing at Chicago, in the county of Cook and State of Illinois, have invented a new, original, and ornamental Design for Live Bait Carrier, of which the following is a specification, reference being had to the accompanying drawing, forming part thereof, in which:

Fig. 1 is a perspective view of a live bait carrier showing the side and one end thereof, embodying my new design;

Fig. 2 is a perspective view of the live bait carrier showing the opposite side and opposite end thereof with the supporting rope in carrying position; and

Fig. 3 is an end view of the live bait carrier supported by the carrying rope in upright position

as distinguished from the horizontal positions shown in Fig. 1 and in Fig. 2.

I claim:

The ornamental design for a live bait carrier, substantially as shown.

RUFUS D. BLAKESLEE.
